Term of patent 14 years

Int. Cl. D12—11, 14
U.S. Cl. D90—1

FIGURE 1 is a side elevation of a hydraulic bicycle brake showing our new design;

FIGURE 2 is a front perspective view thereof, and
FIGURE 3 is a rear perspective view thereof.

The bicycle shown fragmentarily and in broken lines in FIGURE 1 is included for illustrative purposes only.

The characteristic feature of our design resides in the specific configuration of the hydraulic cylinder with its tapered and rounded ends and in the angularly positioned nipple extending from one of said rounded ends all as shown.

We claim:

The ornamental design for a hydraulic bicycle brake, as shown and described.
